UNITED STATES PATENT OFFICE

2,605,446

INCANDESCENT LAMP

Paul O. Cartun, Cleveland Heights, Ohio, assignor
to General Electric Company, a corporation of
New York

Application June 1, 1951, Serial No. 229,372

4 Claims. (Cl. 315—120)

1

My invention relates to electric incandescent lamps which are adapted to be operated in series, and more particularly to a lamp of such type having means associated therewith for indicating a breakage or failure of the filament within the lamp.

Certain types of electric incandescent lamps, such for example as those employed for Christmas tree lighting and which may be termed "miniature" lamps, are operated by connecting a given number of the lamps in series whereby the combined voltages of the several lamps equal the line voltage supplying the electrical energy. However, when used in such manner, considerable inconvenience occurs upon a failure of one of the lamps, as for instance when a filament breaks or burns out, since such failure interrupts the continuity of the circuit and the rest of the lamps in the circuit are extinguished. When a string or plurality of series-connected lamps become thus extinguished because of such failure it is difficult to determine which lamp is defective. In order to discover the lamp which has failed it becomes necessary to separately test each lamp of the series until the defective lamp is found. This procedure involves considerable time and inconvenience and has heretofore caused considerable annoyance in connection with series-burning lamps.

It is an object of the present invention, therefore, to provide an electric incandescent lamp operable to give a positive visible indication of a failure in the filament of a lamp.

Another object of the invention is to provide an electric incandescent lamp operable to energize an auxiliary filament therein and simultaneously form a coating on the lamp envelope which imparts a distinctive appearance to the lamp upon failure of the main filament.

Still another object of the invention is to provide an electric incandescent lamp having an auxiliary filament therein which is automatically connected into the lamp circuit upon failure of the main filament and the energization of which causes the deposition of a substantially light-impermeable coating on the inner surface of the lamp envelope.

In accordance with the invention, an incandescent lamp for series operation is provided with main and auxiliary filaments shunted at one end by a normally insulative cut-out or shunt which, upon failure of the main filament, becomes conductive and operative to connect the auxiliary filament into the lamp circuit. The auxiliary filament of the lamp is provided, in ad-

dition, with a quantity of a readily vaporizable material which, upon energization and heating of the auxiliary filament, is vaporized off the filament and is flashed or deposited onto the interior surface of the envelope to form a distinctive coating. Preferably, the said vaporizable material is a metal, such as magnesium for example, which forms a substantially light-impermeable coating on the envelope which prevents transmission of the light from the auxiliary filament and thus gives to the lamp a darkened or unlighted appearance providing a visible indication that the lamp is defective or burned out.

Further objects and advantages of my invention will appear from the following detailed description of species thereof and from the accompanying drawing in which:

Fig. 1 is a longitudinal section of an electric incandescent lamp according to the invention; Fig. 2 is an elevation of a modified form of lamp according to the invention, and Fig. 3 is an elevation of another modification.

Referring to Fig. 1 of the drawings, the invention is there shown as applied to an electric incandescent lamp of the double-ended type comprising a sealed elongated glass envelope or bulb 1 provided at its ends with base members 2 and 3 and having a pair of filaments 4 and 5 mounted therein constituting, respectively, main and auxiliary filaments. In the particular case illustrated, the main and auxiliary filaments 4, 5 are constituted by a single length of tungsten or other suitable filament wire provided with coiled portions or segments which form the main and auxiliary filaments 4, 5 and which are joined by an intermediate bight portion 6. The two filaments 4, 5 may, however, be formed as entirely separate members, if desired. The auxiliary or secondary filament 5 may be of substantially the same resistance as the main or primary filament 4. In the form of the invention shown in Fig. 1, the two filament portions 4, 5 extend alongside one another in a direction more or less lengthwise of the elongated envelope 1.

The filaments 4, 5 are supported in place by relatively rigid lead-in conductors or wires 7 and 8 sealed through the opposite ends of the envelope and electrically connected, respectively, to the bases 2 and 3. Conductor 7 is connected to the intermediate or filament bight portion 6 joining the main and auxiliary filament portions 4 and 5 at one end thereof, while lead-in conductor 8 is connected to the other end of the main filament portion 4. The other or free end of the auxiliary filament portion 5 is con-

ected to a relatively rigid dummy current conductor 9 which extends alongside the lead-in conductor 8 and is supported in place therefrom by a cut-out or shunt member 10 which bridges and ties together the two conductors 8, 9.

The cut-out or shunt 10 is of a type which is normally non-conductive when the normal voltage of the single lamp is applied thereacross but which becomes conductive when a higher voltage is applied to it such as occurs when the main filament 4 becomes broken or otherwise fails. The particular cut-out 10 illustrated comprises a pair of closely spaced beads 11, 12 of suitable insulating material, such as powdered silica or glass, fusion-sealed around and bridging the conductors 8, 9 and having the space between the beads filled with a suitable cut-out material 13 so as to surround and bridge the said conductors 8, 9. The cut-out or shunt material 13 may be, for instance, of the type described and claimed in U. S. Patent 1,992,844, Severin et al., and comprising a mixture of a metal powder such as iron powder, a finely powdered insulating material such as cryolite powder, and a binder such as sodium silicate. Under ordinary operating conditions the sodium silicate and cryolite give the mixture insulating properties, but upon failure of the main filament 4 of the lamp when connected in series the increase in voltage across the lamp terminals is such that the resistance of the cut-out is insufficient to prevent the current from passing from one conductor 8 to the other conductor 9.

In a preferred form of the invention, the auxiliary filament 5 is provided with a coating 14 of a readily vaporizable material, such as magnesium or aluminum for example, which is vaporized or flashed off the filament upon energization and resultant heating thereof and which will then deposit on the envelope wall in sufficient quantity to form a substantially light-impervious or opaque coating thereon. The coating 14 may conveniently be in the form of a bead constituted of a paste made from fine magnesium powder mixed with and held together by a suitable binder such as nitrocellulose dissolved in amyl acetate, for example.

It will be obvious that the vaporizable material 14, instead of being one which produces an opaque coating, may be a material such as lead oxide or cadmium sulphide which produce a colored, diffusing or other distinctive coating.

In the normal series operation of the lamp according to the invention, the normal operating voltage of the single lamp is applied to the cut-out or shunt 10. However, since the cut-out or shunt 10 is non-conductive at such normal operating voltage of the lamp, the current will therefore pass through the main filament 4 only. Upon a failure of the main filament 4, however, the full line voltage applied across all the lamps in the series is then applied across the conductors 8, 9 and to the cut-out material 13 therebetween, causing a break-down of the insulating oxide or dielectric in the cut-out material 13 which therefore renders the latter conductive and permits the passage of current between conductors 8 and 9 and consequently a flow of current through the auxiliary filament 5 as well as through the remaining lamps in the series. The resulting energization and heating of the auxiliary filament 5 vaporizes the magnesium or other vaporizable metal contained in the coating or bead 14 thereon, which vaporized metal then condenses on the inner surface of the envelope wall to form a sub-

stantially light-impervious or opaque coating thereon. The resulting absorption or obstruction by such coating of the light from the energized auxiliary filament 5 gives the lamp a darkened appearance which clearly distinguishes it from the other operating lamps in the series by reason of their normal lighted appearance, and which therefore provides a ready visible indication of the particular lamp in the series which has failed.

The modification shown in Fig. 2 differs from the construction shown in Fig. 1 principally in that it employs a simplified form of filament construction wherein the main and auxiliary filament portions 4', 5', together with their interconnecting straight bight portion 6', are arranged in a substantially straight line extending diagonally to the longitudinal axis of the envelope 1, with the intermediate bight portion 6' located substantially in the said axis where it is clamped or otherwise connected to the lead-in conductor 7. The opposite ends of the filament 4', 5' are connected, respectively, to the conductors 8' and 9', as before.

Fig. 3 illustrates the application of the invention to a lamp of a single-ended type such as is generally used for Christmas tree lighting and comprising a sealed glass envelope 15 provided with a single neck end into which a mount 16 is butt-sealed. The mount 16 comprises lead-in wires or conductors 7'' or 8'' which are butt-sealed through the neck end of the envelope and are connected to the terminals, e. g., the base shell 18 and eyelet 19, of a conventional base 17 suitably fastened to the neck end of the envelope, as by basing cement for instance. A dummy conductor 9'' extends alongside the lead-in conductor 8'' and is supported therefrom in normally insulated relation by the normally non-conductive cut-out or shunt 10 which may be of the same construction as that shown in Figs. 1 and 2 and which bridges the two conductors 8'', 9'' but does not contact the other conductor 7''. The three conductors 7'', 8'' and 9'' support a V-shaped filament comprised of coiled main and auxiliary leg portions 4'' and 5'', respectively, joined at the apex of the filament by a connecting bight portion 6''. Conductor 7'' is connected to the intermediate bight portion 6'' of the filament while conductors 8'' and 9'' are connected to the free ends of the coiled main and auxiliary filament portions 4'' and 5'', respectively. The coiled auxiliary filament portion 5'' is provided with a coating or bead 14 of a readily vaporizable metal such as magnesium, the same as in Figs. 1 and 2.

As in the case of the lamps of Figs. 1 and 2, the normally non-conductive cut-out 10 of the lamp shown in Fig. 3 becomes conductive upon failure of the main filament 4'' and thus connects the auxiliary filament 5'' into the lamp circuit. The resulting energization and heating of the auxiliary filament 5'' then vaporizes the magnesium or other vaporizable metal in the bead 14 to form a light-impervious coating on the envelope wall which then blocks the light emitted by the auxiliary filament and gives the lamp a darkened appearance readily distinguishing it from the other normally lighted lamps in the series and indicating it as a defective lamp.

Although preferred species of my invention have been disclosed, it will be understood that the invention is not to be limited to the specific constructions and arrangements of parts shown, but that they may be widely modified within the

spirit and scope of my invention as defined by the appended claims.

What I claim as new and desire to secure by Letters Patent of the United States is:

1. An electric incandescent lamp comprising a sealed envelope, a main filament and an auxiliary filament in said envelope electrically interconnected at one of their respective ends, a pair of lead-in wires sealed through said envelope, one of said lead-in wires being electrically connected to the said interconnected ends of said filaments and the other of said lead-in wires being electrically connected to the other end of said main filament, an electrical conductor connected to the other end of said auxiliary filament, a cut-out bridging the said other lead-in wire and the said electrical conductor, said cut-out being non-conductive when the normal operating voltage of the lamp is applied thereto but becoming conductive when a higher voltage is applied to it, and a quantity of a readily vaporizable material on said auxiliary filament adapted to be vaporized therefrom onto the envelope upon energization of said auxiliary filament.

2. An electric incandescent lamp comprising a sealed envelope, a filament in said envelope, a pair of lead-in wires sealed through said envelope, one of said lead-in wires being electrically connected to an intermediate point of said filament and the other of said lead-in wires being electrically connected to one end of said filament, an electrical conductor connected to the other end of said filament, a cut-out bridging the said other lead-in wire and the said electrical conductor, said cut-out being non-conductive when the nor-

mal operating voltage of the lamp is applied thereto but becoming conductive when a higher voltage is applied to it, and a quantity of a readily vaporizable material on the portion of said filament connected to said electrical conductor and adapted to be vaporized therefrom onto the envelope upon energization of the said portion of the filament.

3. An electric incandescent lamp comprising a sealed envelope, a filament in said envelope comprising a main portion and an auxiliary portion joined by a bight portion, a pair of lead-in wires sealed through said envelope, one of said lead-in wires being electrically connected to said bight portion and the other of said lead-in wires being electrically connected to the free end of said main filament portion, an electrical conductor electrically connected to the free end of said auxiliary filament portion, a cut-out bridging the said other lead-in wire and the said electrical conductor, said cut-out being non-conductive when the normal operating voltage of the lamp is applied thereto but becoming conductive when a higher voltage is applied to it, and a quantity of a readily vaporizable material on the auxiliary filament portion adapted to be vaporized therefrom onto the envelope upon energization of the said auxiliary filament portion.

4. An electric incandescent lamp as set forth in claim 1 wherein the said vaporizable material comprises a bead of magnesium.
